E. E. BROSIUS

CIGARETTE HOLDER CASE

Filed April 19, 1926

UNITED STATES PATENT OFFICE.

EDWARD E. BROSIUS, OF SPOKANE, WASHINGTON.

CIGARETTE-HOLDER CASE.

Application filed April 19, 1926. Serial No. 102,908.

My present invention relates to a combined cigarette-holder case and pencil especially adapted for pocket use or personal wear, and designed to provide a sanitary receptacle for the cigar or cigarette-holder when the latter is not in use, and also for use as a lead pencil of the type involving a screw feed for the lead. As is well known to those familiar with the use of cigars and cigarettes, a holder is a desirable and necessary accessory, from various points of view, and the purpose of my invention is to provide such a case for the holder that may with convenience be carried in the pocket and which also combines therewith a lead pencil, thus utilizing in the one article two devices or articles that are usually separated. By this combination of elements or articles both the cigarette-holder case and the lead pencil are readily accessible for use when needed and means are provided whereby the combined article may be retained in the pocket and occupy a minimum of space therein for such articles.

The case forms a sanitary receptacle or enclosure for the cigarette holder when not in use and at the same time also forms a part of the pencil structure in affording the necessary length of the standard size of pencils.

The invention consists in certain novel combinations and arrangements of parts involving the pencil in which the cigarette-holder case is embodied as will hereinafter be more fully set forth and claimed.

In the accompanying drawings I have illustrated one complete example of the physical embodiment of my invention wherein the parts are combined and arranged in accordance with the best mode I have thus far devised for the practical application of the principles of my invention.

Figure 1 is an enlarged vertical sectional view of the combined cigarette-holder case and pencil, showing the cigarette-holder partly broken away for convenience of illustration.

Figure 2 is a perspective view of the interior magazine for extra leads.

Figure 3 is an enlarged detail vertical sectional view of the lead propelling or projecting device, at line 3-3 Fig. 1.

Figure 4 is a perspective view of an absorbent cap used on the magazine for cleaning the interior of the cigarette holder.

Figure 5 is a transverse sectional view at line 5-5 of Figure 1.

Figure 6 is a transverse sectional view at line 6-6 of Fig. 2.

In carrying out my invention I utilize a tubular cap portion 1 of suitable material, size and shape having an open lower end with inwardly tapering wall or surface and a closed end in which an eraser as 2 is threaded. The eraser may be of rubber or composition material and is used for erasing pencil marks etc. The cap 1 forms the cigarette-holder case and is provided with a spring slip 3 of well known type by means of which the combined article is retained in the pocket as usual. Within the case 1 is enclosed the cigarette-holder 4 which is of standard size and shape and manufactured of appropriate material with exterior screw threads 5 between its body and the mouth-piece.

The case 1 is fashioned with complementary, interior screw threads 6 for co-action with the exterior threads of the holder and it will be apparent that the holder is secured in its case by means of the threaded engagement with the mouth-piece encased in the closed end of the case. The holder is carried in inverted position as shown with its outer end projecting beyond the open end of the case, and the open end of the case with its inner tapered end forms a friction joint with the exterior-tapered end 7 of the tubular body or barrel of the pencil indicated as 8. The barrel, which is cylindrical in form is open at both ends and is fashioned with a reduced bore at its upper tapered end to provide an annular, interior shoulder 9 against which the head 10 of a magazine-tube 11 snugly fits, and the head 10 as seen in Figure 1 also forms an abutment for the outer open end of the cigarette-holder.

At its lower end the magazine-tube is fashioned with an enlarged, circular head 12, and the lower end of the barrel enclosing the magazine-tube fits against this head 12.

To gain access to the magazine-tube for loading it or for withdrawing fresh leads therefrom, the wall of the tube is fashioned with a vertical slot 13 in which a slide gate or clip 14 is located. The gate frictionally engages the side walls of the slot and the former may be slid to one end of the slot 100 to permit introduction to or withdrawal of

leads from the interior of the magazine through the slot, after which the gate is slid to approximately central position in the slot to prevent displacement of the remaining 5 leads enclosed in the magazine.

The lead holder of the pencil is carried at the longitudinal center of the device within the heads 10 and 12 of the magazine which are fashioned with central openings 10 for this purpose, and the lead 15 is clutched at its upper end between a pair of resilient gripping jaws 16 and 17.

These jaws are fashioned integral with a propelling screw 18 in the form of a tube 15 having a spiral or screw groove 19 in its outer face. The screw is movable longitudinally of a holder-tube 20 in which it is encased and the tube or sleeve 20 is provided with interior, spiral ribs or screw threads 21 complementary to the grooves of the screw 18.

It will be understood that the sleeve 20 is fixed and the screw 18 and the lead 15 are movable with relation thereto to project or 25 retract the lead 15. The upper closed end 22 of the screw-holder or sleeve 20 projects upwardly through the head 10 of the magazine tube, and on this closed end is fixed a cap 23 of suitable absorbent material as seen 30 in Figure 1 over which the open outer end of the cigarette-holder slips and fits neatly. When placed in position in its case the cigarette-holder is slipped over this absorbent cap and this movement wipes the interior 35 walls of the cigarette holder to clean them of nicotine or other accumulation in the bore of the holder.

At its lower end the enclosing sleeve 20 has an exterior, annular flange 24 located 40 below the head 12 of the magazine, and this flange is encased within a countersunk head 25 of the conical or tapered pencil point 26 which is rotatable with relation to the body of the pencil for propelling the lead 15. 45 The head 12 of the magazine body may have an annular retaining flange 26' into which the head of the pencil point 26 fits and in

which it rotates, the edge being crimped over the head as best seen in Figure 1.

The lead is projected or propelled from its 50 holder by rotation of the pencil point 26, the body of the pencil of course being held stationary during the turning movement of the pencil point, and the countersunk head 25 of the pencil point turns about the annular flange 24 of the holder sleeve as a center.

The tapered pencil point 26 is preferably hollow with an opening in its pointed end for the lead to project through, and within the hollow pencil point is provided an offset, guide bar 27 fixed to rotate with and carried by the pencil point. This bar contacts with one of the jaws, as 16, which has a groove 28 for the bar, for coupling the lead screw 18 with the pencil-point 26 in order that these members may rotate together. Thus as the pencil point is rotated and retained against longitudinal movement, the lead-screw 18 is also rotated and also given a longitudinal movement, in which latter movement it is guided by the grooved jaw 16 sliding along the guide bar 27.

Having thus fully described my invention, what I claim as new and desire to secure 75 by Letters Patent is—

1. A device of the class described, comprising a case, a cigarette holder engaged therein, a barrel engaged with the case, a tube mounted in the barrel, a cap of absorbent material carried by the tube for engaging the socket of the holder when the case and barrel are interlocked with each other, as and for the purpose set forth.

2. The combination with a case, of a cigarette holder having threaded engagement therewith, one end of said holder being extended from the case and a barrel enclosing the extended end of the holder, and means associated with the barrel for cleansing the 90 socket of the holder.

In testimony whereof I affix my signature.

EDWARD E. BROSIUS.
